UNITED STATES PATENT OFFICE.

HENRY M. FULLER, OF SALT LAKE CITY, UTAH,

AIR-REGULATING VALVE.

1,247,951.

Specification of Letters Patent.

Patented Nov. 27, 1917.

Application filed September 17, 1917. Serial No. 191,881.

To all whom it may concern:

Be it known that I, HENRY M. FULLER, a citizen of the United States, residing at Salt Lake City, in the county of Salt Lake 5 and State of Utah, have invented certain new and useful Improvements in Air-Regulating Valves, of which the following is a specification.

My invention relates to internal combustion engines, and has for its object to provide an air valve for use between the carbureter and the cylinders whereby a more perfect mixture is secured than has previously been secured.

15 To develop power with internal combustion engines, a carbureter is used to volatilize and mix explosive fluids with air, to provide the required explosive gas, and as at different altitudes, and under different 20 conditions of the atmosphere adjustments must be made in the carbureter to provide this proper mixture, and the engine must be stopped to make said adjustments. The present invention enables me to supply more 25 air to the carbureter mixture after the carbureter has acted, and thus provide the required and proper mixture without stopping the engine. A further object is to provide a device which will prevent the drawing 30 into the cylinders of minute particles of liquid fuel by supplying an adjustable valve whereby air may be supplied to volatilize these minute particles of liquid fuel and mix with the gas from said minute particles 35 between the carbureters and cylinders, so that when introduced into the cylinders with the mixture made in the carbureter the whole of the introduced mixture will be proper and instead of their loss power will 40 be obtained from these minute particles.

These objects I accomplish with the device illustrated in the accompanying drawings in which similar letters and numerals of reference indicate like parts throughout 45 the several figures and as described in the specification forming a part of this application and pointed out in the appended claims.

Figure 1 is a diagrammatic view of a four 50 cylinder engine with my device in place thereon. Fig. 2 is an elevation of the plunger and a portion of the rod. Fig. 3 is an elevation of the valve showing one port. Fig. 4 is an elevation of the slideable sleeve. Fig. 5 is an elevation of the casing. Fig. 6 55 is an elevation of the distributor in place

on the elbow connection of the device. Fig. 7 is a plan view showing all the ports of the valve. Fig. 8 is a longitudinal section of the device.

The present invention is shown on a four cylinder engine A, but as will be obvious it may be used on engines having a greater or a lesser number of cylinders and consists of the construction and arrangement of parts 60 as hereafter described. The device consists of a casing 1 having elongated slots 2 in its walls. One end of said casing is closed except for the axial opening through which the plunger rod is operated. Into the other 65 end of said casing the elbow 3 is screwed and an internally and externally threaded thimble 4 is used to secure the device in the intake manifold B. The valve 5 is threaded at one end and is secured in place by screwing it into the end of said elbow 4, and concentric with said casing. The wall of 70 said valve is longitudinally slotted from one end, to near the threads on its other end, to provide air ports, a, b, c, and d as clearly 75 shown in Fig. 7. To increase the size of said ports for purposes hereafter explained, holes or enlargements, a', b', c' and d' are bored cutting the walls of said ports. A 80 plunger 6 is operated within said valve by 85 means of the rod 7 which is passed through the axial opening in the closed end of said casing 1. A sleeve 8 is carried on said rod 7 and operated concentrically within said casing 1 and over said valve 5. A jam nut 90 9 is screwed on said rod 7 to hold the end closure of said sleeve against the closed end of said plunger 6. The lower ends of said plunger 6 and of said sleeve 8 are on the 95 same plane and as one closes the ports on the inside and the other on the outside they 100 coact to regulate the flow of air through the ports. The carbureter is shown at C and the device is fastened to the dashboard D of the vehicle by passing said rod 7 through said dashboard.

The operation of my valve is as follows:—

With the air and liquid fuel mixed in the carbureters now in use, and desiring to secure greater power from the engine for 105 climbing hills the additional air required may be supplied by drawing the rod 7 longitudinally toward the said dashboard D to open the ports a', b, c, and d by moving the plunger 6 and sleeve 8 from over said ports. 110 The first hole a' and portions of the slots b, c, and d will be uncovered to allow air to

enter the intake manifold. If more air is required the plunger and sleeve are moved to open the next hole b' in said slot b and more of the slots a , b , c , and d , and when said hole b' is open the hole a' is also open and air will pass through holes a' , b' and portions of the slotted ports, a , b , c and d . The position of the holes and the use of the holes and slotted ports enable me to gradually increase or decrease the air through the valve. I also provide a distributor by screwing a T-shaped plug 10 into said thimble 4 which divides the air and directs it to the right and left to prevent one cylinder from receiving more than its share of the air introduced through the valve.

Having thus described my invention I desire to secure by Letters Patent and claim:—

1. An air regulating valve consisting of a casing having elongated slots in its walls; a cylindrical valve seat concentrically secured within said casing and having air ports cut in its wall; a plunger valve operable within said valve seat; and a sleeve casing concentrically fastened to said plunger valve and slidably operated to open and close said air ports.
2. In combination with the intake mani-

fold of an internal combustion engine, a casing having elongated slots in its wall and secured in said intake manifold; a cylindrical valve seat concentrically spaced from and secured within said casing, and provided with longitudinally disposed slots in its wall; and a plunger valve and a sleeve concentrically spaced apart and slidable along said cylindrical valve seat to open and close said longitudinal slots.

3. In combination with the intake manifold pipe of an internal combustion engine; a slotted casing fastened on and opening into said intake manifold; a cylindrical valve seat concentrically spaced from and fastened within said casing having elongated slots cut in its wall and holes enlarging said slots at increasing distances from the ends; a plunger valve operated within said valve seat and a sleeve concentrically fastened on said plunger valve and operated between said valve seat and said casing, the plunger and sleeve coacting to open and close said ports.

In testimony whereof I have affixed my signature.

HENRY M. FULLER.
